ARTICLE OF APPAREL

Ruth M. Rountadt, Pennington, Ariz.

Application November 8, 1946, Serial No. 708,768

5 Claims. (Cl. 2-75)

1

This invention relates to an article of apparel and to a construction particularly adapted for infant wear which is simple to make and readily laundered and ironed as a simple, flat, folded piece of cloth and which at the same time when worn presents an attractive appearance. Heretofore, children's garments of simple construction which could be readily ironed in a mangle and which lie flat when laid out for ironing have been rather loose fitting when worn and of such simple 10 lines as to be unattractive.

It is an object of the present invention to provide a dress which combines attractive appearance with ease in laundering and ironing.

Figure 1 is a front view of the dress in the laid out, flattened condition.

Figure 2 is a rear view of the dress in the flat.

Figure 3 is a front view of the dress in the shape as worn.

Figure 4 is a rear view of the dress as worn.

Referring now to the drawings, the dress comprises a lower skirt section 10 and an upper blouse section 12. The skirt section is formed of tubular shape and may be either straight sided as illustrated or may be wider at the bottom than the top. In either event, the skirt forms a circumferentially continuous tube about the wearer and there are no openings at front, back or side. The top of the skirt section is open around its entire circumference and is provided with a hem 14 having a drawstring 16 by which the top may be gathered.

The blouse section 12 is formed of one or more flat pieces of fabric which are folded over the shoulder portions 18 and formed with straight sides 20 and has a straight bottom stitched to the top of the skirt 10 at the front and at the back. The width of the blouse portion 12 is substantially less than the width of the skirt 10 when flattened out as shown in Figure 1 leaving open rectangular notches 16' at either side. Likewise, the front and back panels of the blouse 12 are not secured to each other except where they are joined at the top across the shoulder portions 18. A suitable neck opening 22 is provided with a hem and drawstring 24.

It will be seen that the article may be laid completely flat as illustrated in Figures 1 and 2 and that the tubular skirt folds upon itself along the side edges while the blouse panels fold upon themselves along the top edges 18. The article is thus readily ironed, there being no pleats, gathers or shaped portions whatever to the garment when thus laid out. It is particularly adaptable for ironing in a mangle.

2

When the dress is to be worn, it may be slipped over the head of the wearer and the arms extended through the openings formed between the front and back panels of the blouse 12. The rectangular notches 16 provide adequate room for this purpose even though the waist line at the hem 14 be very high and substantially under the armpits as in the preferred construction.

When the drawstrings 16 and 24 are drawn up and tightened, the dress presents the appearance shown in Figures 3 and 4. This brings the neckline down to a size of more pleasing appearance than if it were permitted to remain extended. It is necessary, of course, that the neck opening 22 be large enough to pass over the head. The drawstring 16 gathers the skirt and the front and rear panels of the blouse in a plurality of pleats and folds. By reason of the extra material provided in the skirt at the rectangular notches 16', a pleasing effect is obtained due to drawing the lower edges of the blouse panels together. This creates the blouse contour at the arm line shown in Figures 3 and 4 which tapers inwardly toward the bottom. At the same time adequate room for arm movement is provided by the extra material at the top of the skirt underneath the arms.

While this invention has been described in the form particularly adapted for infant wear, it will be understood that the principles thereof may be incorporated in any other articles of apparel for persons of all ages such as ladies' dresses, nightgowns and similar articles. It will also be understood that the blouse section 12 and the skirt section 10 may be formed from one piece of material folded upon itself along the top edges of the blouse as at 18 and stitched along each side of the skirt section as at 26. When formed in this manner, rectangular notches 28 will be cut out from the upper corners of the folded material to provide openings for arms to extend through and neck opening 22 will be similarly cut at the top edge of the blouse section.

I claim:

1. An article of apparel such as a dress, gown or the like comprising an upper blouse section and a lower skirt section, said skirt section being formed of a circumferentially continuous tubular section of fabric normally having a much greater circumference than the body of the wearer with a drawstring for gathering the top of the skirt when on the wearer, said blouse section comprising a flat panel folded flatly upon itself across the shoulders to form flat front and rear panels for said blouse, the lower edges of

said front and rear panels being fastened in the flat to the ungathered top of the skirt to be gathered therewith, the width of the front and rear panels being less than the flattened ungathered width of the skirt top and substantially greater than the waist of the wearer, said blouse being open at the sides from the shoulders to the waist to provide arm holes and having a neck opening also provided with a drawstring whereby the article may lie completely flat for ironing with only the skirt folded along its vertical sides and the blouse folded along the top.

2. An article of apparel such as a dress, gown or the like comprising an upper blouse section and a lower skirt section, said skirt section being formed of a circumferentially continuous tubular section of fabric having a circumference much great than the body of the wearer with a drawstring for gathering the top of the skirt when on the wearer, said blouse section comprising a flat panel folded flatly upon itself across the shoulders to form flat front and rear panels for said blouse, the lower edges of said front and rear panels being fastened in the flat to the ungathered top of the skirt to be gathered therewith, said blouse being open at the sides and said skirt extending substantially beyond the sides of the blouse whereby the article may lie completely flat for ironing with only the skirt folded along its vertical sides and the blouse folded along the top and may be gathered by said drawstrings to conform to the figure of the wearer.

3. An article of apparel such as a dress, gown or the like comprising an upper blouse section and a lower skirt section, said skirt section being formed of a circumferentially continuous tubular section of fabric with a drawstring for gathering the top of the skirt and having a circumference substantially greater than the body of the wearer, said blouse section comprising a flat panel folded flatly upon itself across the shoulders to form flat front and rear panels for said blouse, the lower edges of said front and rear panels being fastened in the flat to the ungathered top of the skirt to be gathered therewith, said blouse being open at the sides from the shoulders to the waist and said skirt extending substantially beyond the sides of the blouse whereby the article may lie completely flat for ironing with only the skirt folded along its vertical sides and the blouse folded along the top, said blouse having a neck opening provided with a drawstring whereby the article may be gathered

into pleats both at the waist and neck to conform to the figure of the wearer and retain fullness at the ungathered portions.

4. An article of apparel such as a dress, gown or the like comprising an upper blouse section and a lower skirt section, said skirt section being formed of a circumferentially flat continuous tubular section of fabric with a drawstring for gathering the top of the skirt, said blouse section comprising a flat panel folded flatly upon itself across the shoulders to form flat front and rear panels for said blouse, the lower edges of said front and rear panels being fastened in the flat to the ungathered top of the skirt to be gathered therewith, said blouse being open at the sides and said skirt extending substantially beyond the sides of the blouse, said skirt top extending to a point just short of the armpits of the wearer and having a circumference substantially greater than the body of the wearer.

5. An article of apparel, such as a dress, gown or the like comprising a flat rectangular panel folded upon itself along the mid line between its ends to form a front and rear panel for said article, said front and rear panels each extending from the shoulders to at least the region of the knees of the wearer, a neck opening centrally disposed along the folded end, rectangular portions removed at each side of said folded panel adjacent the folded end thereof and extending down to the waist line of the wearer, the side edges of said front and rear panels being unconnected from the waist line upwardly to said folded end and being fastened together from the waist line down to the lower edges of said front and rear panels and drawstrings at the neck opening and waist line whereby the article may be ironed as a flat panel and may be gathered into pleats at both the waist and neck when on the wearer to conform to the figure of the wearer.
